CLAIM

The ornamental design for a single vent directional reamer tip, as shown and described.

DESCRIPTION

FIG. 1 is a front perspective view of the single vent directional reamer tip comprising the new design;

FIG. 2 is a right elevational view of the design of FIG. 1, where the left elevational view is a mirror image;

FIG. 3 is a top view of the design of FIG. 1;

FIG. 4 is a bottom view of the design of FIG. 1;

FIG. 5 is a front elevational view of the design of FIG. 1;

FIG. 6 is a back elevational view of the design of FIG. 1; and,

FIG. 7 is another perspective view of the single vent directional reamer tip design of FIG. 1.

The broken lines shown in the figures represent portions of the single vent directional reamer tip that form no part of the claimed design.

The broken away symbols in the drawings indicate that any portion of the article beyond what is shown forms no part of the claimed design.
